(57) **CLAIM**

The ornamental design for a nosepick, as shown and described.

DESCRIPTION

FIG. 1 is a perspective view.

FIG. 2 is a right side view

FIG. 3 is a left side view

FIG. 4 is a back view

FIG. 5 is a front view

FIG. 6 is a top view; and,

FIG. 7 is a bottom view.

The dot-dash broken lines immediately adjacent the shaded areas represent the bounds of the claimed design while all other broken lines represent unclaimed portions of the article. The broken lines form no part of the claimed design.
